TRUSS

Arthur R. Bell, Philadelphia, Pa., assignor to Wm. H. Horn & Brother, Inc., Philadelphia, Pa., a corporation of Pennsylvania

Application March 27, 1935, Serial No. 13,208

8 Claims. (Cl. 128—124)

My invention is an improved surgical apparatus, commonly known as a truss, and consisting of a flexible metal spring or elastic belt adapted for encircling the body and pressing a pad firmly against the body to provide support or hinder protrusion, particularly in the treatment of hernia.

The varying conditions arising in the treatment of hernia necessitate the attachment of pads of different sizes and shapes to belts or truss frames of different types and in different positions thereon. It is a leading object of my invention to provide a truss having means for quickly effecting pad substitutions or changes of position of the pad on a truss frame which may be of either the slotted or unslotted type and to which the pad is securely but detachably secured by a fastener or hasp keyed against turning relatively to the truss frame.

By my improvements, a dealer having a stock of comparatively few truss frame units and comparatively few pad units and fasteners is enabled to quickly assemble therefrom a truss suitable for use under any one or more of a wide variety of conditions. The units, when assembled, are securely maintained in desired relation to one another by the quick detachable fasteners consisting of hasps containing apertures, one or more of which is an open slot extending to the edge of the hasp. The pads are provided with studs sufficiently spaced from one another for the passage of an unslotted truss frame section between them, and the studs are of such cross-section as to readily pass through the slot of a slotted belt section. The studs have shanks of such cross-section as to pass readily through the apertures or slots of the hasps, which are movable normal to the axis of the studs into engaging or disengaging position.

The characteristic features and advantages of my improvements will further appear from the following description and the accompanying drawing in illustration thereof.

In the drawing, Figure 1 is a perspective view of a slotted spring truss having a pad connected therewith in accordance with my improvements; Fig. 2 is a perspective view of an imperforate spring truss having connected therewith the same pad as shown in Fig. 1; Fig. 3 is an enlarged elevation of the pad and attachment and a fragment of the metal spring of Fig. 1; Fig. 4 is a transverse sectional view taken on the line 4—4 of Fig. 3; Fig. 5 is an enlarged elevation of the pad and attachment and a fragment of the metal spring of Fig. 2; Fig. 6 is an elevation of a differ-

ent type of pad and modified attachment applied to the spring of Fig. 2, of which a fragment only is shown; and Figs. 7, 8, 9 and 10 are perspective views of modified forms of hasps used in fastening any type of pad to either type of belt in accordance with my invention.

As illustrated in the drawing, the body-encircling truss frame consists of an elastic belt composed of flexible sheath sections 1, housing the end section of an elastic steel spring 2.

As illustrated in Figs. 1, 3 and 4, the intermediate spring section 3 exposed between the sheath sections 1, contains elongated slots 4, whereas, as illustrated in Figs. 2, 5 and 6, the intermediate spring section 5, exposed between the sheath sections 1, is an imperforate narrow strip.

The truss frame is designed to support and press against the body one or more pads of any desired shape and construction, typified generally by the stuffed pad 6, shown in Figs. 1 to 5, inclusive, and by the hard rubber pad 7, shown in Fig. 6.

As illustrated in Figs. 1 to 5, inclusive, the stuffed pad 6 consists of a bag containing a soft packing 6a and a sheet metal plate 8 containing an annular aperture 9 in which the dished or counter-sunk disk 10 is rotatable. A pair of threaded studs 11 pass through apertures in an external disk 12 and are screwed into threaded sockets in the disk 10. The disk 12 acts as a washer to cover the opening 9 and a complementary opening in the bag. The disks 10 and 12 and the studs 11 are rotatable so as to position the studs at any desired angle relative to the perimeter of the pad.

As illustrated in Fig. 6, a pair of threaded studs 11a, similar to the studs 11, are screwed directly into any pair of a plurality of threaded sockets formed directly in the pad.

In accordance with my improvements, each stud has a slotted head and a maximum diameter less than the width of the slots 4. The studs of each pair are sufficiently spaced apart to permit passage of a spring section 5 between them.

A pad is secured to a truss frame or spring by means of a hasp containing apertures for the passage of the studs, and one or more of such apertures consists of an open-ended slot extending to the edge of the hasp and permitting movement of the hasp normal to a stud until the stud is seated at the closed end of the slot.

The hasps may be of different types, as illustrated in Figs. 7, 8, 9 and 10.

As illustrated in Figs. 1, 2, 3, 4, 5 and 7, the hasp 13 contains the apertures 14 consisting of

parallel slots each extending to the edge of the hasp and having an open end at the same side of the hasp. One face of the hasp is provided with keys or feathers 15 adapted to fit into a slot 4 and engage the edges thereof to prevent turning of the hasp. A key-way or channel 16 is formed in the face of the hasp between the keys 15 for the reception of a spring section 5 so that the edges of the spring section engage 10 the keys 15 and the side walls of the channel 16.

To attach a pad to a truss frame having a slotted spring, as illustrated in Figs. 1, 3 and 4, the studs 11 or 11a on a pad are partially unscrewed and inserted through a slot 4 so that 15 the heads of the screws project from the face of the spring section 3 a distance sufficient to permit the slots 14 to be slipped over the shanks of the studs by movement of the hasp normal to the axis of the studs. The keys 15 then slip into the 20 slot 4, and the studs are then tightened up so as to draw the hasp and the pad tightly against the truss frame.

When such pad is to be secured to an unslotted spring section 5, by means of the same hasp, the 25 studs are partially unscrewed and the spring section 5 placed between them so that, as illustrated in Fig. 2, the slots 14 may be slipped over the shanks of the studs by movement of the hasp normal to the axis of the studs. Upon screwing 30 the studs further into the pad, the hasp and pad are tightly clipped on the spring section 5 and prevented from turning angularly relatively thereto by the engagement of the edges of the 35 spring section with the walls of the channel 16 and keys 15.

Instead of having both slots in the hasp open at the same side thereof, the parallel slots may have open mouths at opposite sides of the hasp, as shown in Fig. 8, in which the hasp 13a is provided with slots 14a extending to the edge of the hasp on opposite sides thereof. Keys 15a and a channel 16a are provided for preventing relative turning of the assembled and tightened parts when the hasp 13a is substituted in any of 45 the figures for the hasp 13. In applying the hasp 13a, it is first moved normal to the axis of one stud until such stud is entered in a slot 14a, and the other end of the hasp 13a is then moved normal to the axis of the other stud until the 50 latter is seated in the second slot. The studs are then tightened up to secure the parts together as above described.

As illustrated in Fig. 9, the stud-receiving slots may be normal to one another. As shown in this 55 figure, the hasp 13b is provided with the longitudinal slot 14b having its mouth opening at an end of the hasp and with a transverse slot 14b' having its mouth opening at a side of the hasp. In applying this hasp, it is first moved normal 60 to a stud to slip such stud in the slot 14b and is then moved on such stud as an axis to slip the other stud in the slot 14b'. The keys 15b and channel 16b prevent relative turning of the parts when the studs are tightened up.

65 Where only imperforated springs are used, the hasp need have only one open slot, as shown in Figs. 6 and 10. In such case a hasp 13c may be provided with an aperture 14c through which a stud 11a is passed to permanently attach the hasp 70 to a pad. The hasp is rotatable on such stud when the latter is partially unscrewed so that a spring section 5 may be inserted between the stud passing through the aperture 14c and another stud 11a set in the pad. When the spring section 75 5 has been inserted between the studs, the hasp

is moved in a plane normal to the axis of the studs so as to slip the second stud into the slot 13c' which has an open mouth at one side of the stud.

Having described my invention, I claim:

1. A surgical apparatus consisting of a truss frame adapted for encircling the body and pressing a pad firmly against the body, a pad having a rotatable plate, studs set in said plate and a hasp containing apertures for the passage of said 10 studs, said hasp having a key for engaging an edge of said frame and preventing relative movement of said hasp and frame, said hasp engaging said stud and frame, and at least one of said apertures consisting of an open slot extending to 15 the edge of the hasp and permitting movement of the hasp relative to one of the studs normal to the axis of said stud.

2. A surgical apparatus consisting of a truss frame adapted for encircling the body and pressing a pad firmly against the body, said truss frame containing a slot, a pad having studs connected therewith and movable through said slot, and a hasp containing apertures for the passage of said 20 studs, said hasp having thereon a key 25 between said apertures and entering said slot and engaging the edges thereof, said hasp engaging said studs and a face of said truss frame and securing said key in said slot.

3. A surgical apparatus consisting of a truss frame containing recesses and adapted for encircling the body and pressing a pad firmly against the body, a pad, having studs connected therewith, and a hasp containing apertures for the passage of said studs, said hasp having 30 projections in alignment with the studs adapted to enter said recesses and having a channel intermediate said projections and lying at right angles to the line between the studs and adapted to receive said truss frame, said studs engaging said 40 hasp to draw said hasp and frame together in non-rotative relationship, and at least one of said apertures consisting of an open slot extending to the edge of the hasp and permitting movement of the hasp relative to the studs normal to the axes 45 of such studs.

4. A surgical apparatus consisting of a pad having studs connected therewith, a truss frame having one face thereof engaging said pad, said frame being adapted for encircling the body and 50 pressing a pad firmly against the body, and a hasp engaging a face of said frame opposite the face engaged by said pad and containing apertures for the passage of said studs, each of said 55 apertures consisting of an open slot extending to an edge of the hasp and permitting movement of the hasp relative to the studs and normal to the axes of the studs.

5. A surgical apparatus consisting of a truss frame adapted for encircling the body and firmly 60 pressing a pad against said body, said frame containing a slot, a pad engaging one face of said frame and having studs connected therewith and movable through said slot, and a hasp engaging the face of said frame opposite said pad and containing apertures for the passage of said studs, said hasp engaging said studs, said apertures consisting of open slots extending to the edge of the hasp and permitting movement of the hasp relative to the studs normal to the axes of said studs. 65

6. A surgical apparatus consisting of a truss frame adapted for encircling the body and pressing a pad firmly against the body, a pad having studs connected therewith, and a hasp containing apertures for the passage of said studs, said 75

hasp engaging said studs and frame and said apertures consisting of open slots extending to opposite edges of the hasp and permitting movement of the hasp relative to the studs normal to the axes of such studs.

5 7. A surgical apparatus consisting of a truss frame adapted for encircling the body and pressing a pad firmly against the body, a pad having studs connected therewith, and a hasp containing apertures for the passage of said studs, said hasp engaging said studs and frame and said apertures consisting of open slots normal to one another and extending to the edges of the hasp and permitting movement of the hasp relative to the studs normal to the axes of such studs.

10 15 8. A surgical apparatus consisting of a pad

having studs connected therewith, a truss frame having a part of rectangular cross-section with one face thereof engaging said pad, said frame being adapted for encircling the body and pressing the pad firmly against the body, and a hasp engaging the opposite face of said rectangular part of said frame from said pad and containing apertures for the passage of said studs, said hasp having a key engaging an edge of said rectangular part of said frame and preventing relative movement of said hasp and frame, one of said apertures consisting of an open slot extending to an edge of the hasp and permitting movement of the hasp relative to one of the studs normal to the axis of such stud.
